UNITED STATES PATENT OFFICE

111,875

DESIGN FOR A FONT OF TYPE

Otto C. Goehring, Elmhurst, N. Y.

Application August 31, 1938, Serial No. 79,660

Term of patent 7 years

To all whom it may concern:

Be it known that I, Otto C. Goehring, a citizen of the United States of America, residing at Elmhurst, in the county of Queens and State of New York, have invented a new, original, and ornamental Design for a Font of Type, of which the following is a specification, reference being had to the accompanying drawing, forming a part thereof.

The drawing illustrates a full alphabet of the lower and upper case, numerals and punctuation marks.

The dominant features of my design reside in the use of triangular and spherical members in the formation of the type.

I claim:

The ornamental design for a font of type, as shown and described.

OTTO C. GOEHRING.
